To all whom it may concern:

Be it known that we, Herbert Smith and Melcher Gustaf Werme, both citizens of the United States, residing in Clinton, county of Worcester, and State of Massachusetts, and in Worcester, county of Worcester, and State of Massachusetts, respectively, have invented a new, original, and ornamental Design for a Grille or Similar Article, of which the following is a specification, reference being had to the accompanying drawing, forming a part thereof, in which:

The figure is a plan view of a grille or similar article showing our new design.

We claim:

The ornamental design for a grille or similar article as shown.

HERBERT SMITH.
MELCHER GUSTAF WERME.
